CURRENT-TAPPING CAP-PLUG FITTING

Abraham Abramson, New York, N. Y.

Application July 1, 1932. Serial No. 620,342

1 Claim. (Cl. 173—334)

This invention relates to electric attachment fittings and more particularly is directed to an improvement in a combination current-tapping, cap-plug fitting for detachably connecting one or a plurality of portable electric appliances, lighting systems and the like to an electric power supply outlet receptacle.

Among the objects of the invention is to generally improve the construction of combination current-tapping, cap-plug fitting of the character described, whereby such fitting shall comprise few and simple parts assembled to form a neat appearing, compact, rugged structure, which shall be cheap to manufacture, and which shall be practical and efficient to a high degree in use.

Other objects of this invention will in part be obvious and in part hereinafter pointed out.

The invention accordingly consists in the features of construction, combinations of elements and arrangement of parts which will be exemplified in the constructions hereinafter described and of which the scope of application will be indicated in the following claim.

In the accompanying drawing, in which is shown various possible illustrative embodiments of this invention:

Fig. 1 is a front elevational view of a combination current-tapping, cap-plug fitting constructed to embody the invention, a conventional type of cap-plug being shown in full lines connected thereto.

Figs. 2 and 4 are bottom and top plan views, respectively, of the improved current-tapping, cap-plug fitting shown in Fig. 1.

Figs. 3 and 5 are cross-sectional views taken on lines 3—3 and 5—5 in Fig. 2.

Fig. 6 is a fragmentary cross-sectional view taken on lines 6—6 in Fig. 2.

Fig. 7 is a bottom plan view of a modified construction of the invention, and

Figs. 8 and 9 are fragmentary cross-sectional views taken on lines 8—8 and 9—9 in Fig. 7.

Referring in detail to the drawing, 10 denotes an improved combination current-tapping, cap-plug fitting constructed to embody the invention adapted to connect with conventional baseboards, and fixture socket or flush outlet receptacles in the well understood manner, such fittings 10 having current-tapping portions which in turn are adapted to connect with other fittings 10 or with blades or prongs 12 of conventional cap-plug 11 as shown in Figs. 1 and 5. Said conventional cap-plug 11 may terminate the ends of conductor wires 13 for connecting an electric appliance (not shown) to a suitable

power source through the improved current-tapping cap-plug fitting 10 in the well understood manner.

The current-tapping, cap-plug fitting 10 preferably comprises one piece body portion 14 of any suitable shape and formed of insulating material, such as porcelain, phenol-condensate products or the like moldable substances on which are mounted spaced current-carrying members 15. As here shown, the body portion is cylindrical and may have the members 15 mounted thereon in any suitable manner as by means of drive screws 16 which engage in suitable ledges 14a provided in spaced diametrically opposite portions of the wall of the body 14 inwardly from the peripheral rim portion 14b as is clearly shown in Fig. 6.

The current carrying members 15 may comprise terminal blades or prongs 17 extending outwardly from the bottom or rear side 10a of the body portion 14 and spring contacts 18 which electrically connect in any suitable manner with extensions or bases 17a of the blades 17 when assembled in the body 14. Said contacts 18 extend into a pair of spaced parallelly aligned socket openings 14c provided in the body portion 14. Said openings project down from the top or front side 10b of the said body portion 14 opposite the bottom or rear side 10a as is clearly shown in Figs. 4 and 5. The extensions 17a of the terminals 17 are each provided with a hole for the reception of the drive screw 16 which rigidly anchors the current carrying members 15 to the body portion 14 as is clearly shown in Figs. 2, 3 and 5, the extensions of the base being firmly seated on the ledge 14a. The extensions or bases 17 are also each provided with a threaded hole through which a binding post screw 19 extends for securing the bare end 20a of an appliance conductor wire 20.

The spring contact 18 has one end 18a bent back on itself which is adapted to resiliently engage the blades 12 inserted in the socket openings 14c, said spring contact end 18a being formed with a protuberance 18b for engaging the usual perforation 12a to form a spring releasable interlockment as is clearly shown in Fig. 5. The end 18c of the spring contact 18 opposite the end 18a may be bent and extended to reach under the base 17a beyond the drive screw 16 so that said drive screw when tightened electrically and mechanically unite the blade base 17a with the spring contact end 18c to form the current carrying member 15 into a

rugged structure, as is clearly shown in Figs. 2 and 6.

In order that the fitting 10 be made as compact as possible, the portion 17b of the blade 5 adjacent where the extending prong connects with the base 17a is provided with an offset. This offset is made sufficient to provide a clearance to permit free passage for the leading end of the blades 12 to extend beyond the level of 10 the bases 17a yet allow space for the conductor wires 20 between said offset 17a and the inside wall of the peripheral rim 14b, as is clearly shown in Fig. 5.

To provide an unbroken peripheral rim 14b about the bottom side 10a of the fitting 10 yet allow the conductor wire 20 to extend through the side wall of the body 14, an opening or passage 21 is provided. As one object of the invention is to produce a simple and cheaply constructed fitting, the body portion 14 is structurally formed to permit simple molding operations thereof. To this end, the rim 14b is made larger in diameter than the portion of the body portion extending down from the top side 10b 25 above said rim and thus forms a projecting rim-band. The inner wall 14d of said rim-band preferably aligns with the outer wall portion 14e thereabove, as is clearly shown in Figs. 3, 5 and 6. Thus in molding the body portions 14a, the 30 mold may have a core pin (not shown) extending up into the bottom side 10a and terminating in a form to produce the opening or passage 21, yet leaving the rim-band 14b continuous and unbroken. If desired, the outer surface of the 35 rim-band may be knurled to serve as a finger gripping means.

In using the invention, the current-tapping, cap-plug fitting 10 is connected to the free ends of the conductor wires 20 of an appliance, lighting device, etc. (not shown) through which electric power is supplied to the appliance when the 40 terminal blades are inserted in outlet receptacles in the well understood manner. Other similar appliance or apparatus may successively be connected in circuit by simply plugging in the terminal blades of similar current-tapping, cap plug fittings 10 or of the conventional cap-plug 11 for electrically connecting the blades 12 thereof and the conductor wires 13 to the spring contact 18 as is clearly shown in Fig. 5. The 45 wire 20 passes through the opening 21 at a spaced distance from the bottom or rear side 10a of the fitting 10, so as not to interfere with the seating of said bottom or rear side on the 50 underlying surface of the outlet receptacle.

From the drawing and description given above, it is seen that the fitting 10 is simple and compact in construction and permits connecting a plurality of circuits to a single electric power 60 outlet using one or more of the improved fitting 10 or the latter with a conventional type of cap-plug 11, and in either case, the conductor wire 20 in no way interferes with the seating of such fitting 10 or cap-plug 11. It should also 65 be noted that due to the arrangement of the

current carrying parts 15 the depth or height of the body portion 14 is only slightly greater than the projecting length of the blades 12.

In Figs. 7, 8 and 9, there is shown a modified construction of current-tapping, plug-cap fitting 110. The current-carrying parts here shown are substantially the same as that described above for the fitting 10 with the exception that the spring contact 118 is anchored to the base 17a of the blades 17 by an eyelet rivet 22 instead of being secured thereto by the drive screw 16. A further difference of construction is that instead of having the rim-band 114b of fitting 110 project so far out as the rim-band 14b, there is provided a small extended portion or bulge 114d having the opening or passage 121 for receiving the conductor wire. This form of construction also permits the ready molding of the body portion with a continuous or unbroken rim-band 114b, the passage 121 being molded in the same manner as described above for the passage 21. The fitting 110 is used in the same manner as described above for the fitting 10.

It will thus be seen that there is provided means whereby the several objects of this invention are achieved and which are well adapted to meet the conditions of practical use.

As various possible embodiments might be made of the above invention, and as various changes might be made in the embodiment 105 above set forth, it is to be understood that all matter herein set forth or shown in the accompanying drawing is to be interpreted as illustrative and not in a limiting sense.

Having thus described my invention, I claim 110 as new and desire to secure by Letters Patent:

A current-tapping cap-plug fitting of the character described comprising a one-piece cylindrical shell insulating body having spaced front and rear sides, the front side of said body having socket openings extending perpendicularly thereto into said body, the rear side of said body having thin walled chambers extending therein, identically formed current-carrying spring contact members fitted into said chambers and positioned to align with said openings, terminal blades having extensions aligning and connecting with said members, prong ends for said blades projecting from the rear side, offset portions on said blades to provide clearances for the prong ends of a connecting fitting inserted in said openings when connected with said members whereby the last mentioned prong ends are permitted to extend beyond said extensions and in close proximity to the rear side, a projecting rim-band extending peripherally about the rear side, the body being formed with a passage above and adjacent to said rim-band adapted to receive a conductor wire for connecting with said blades, the inner wall of said rim-band being so constructed and arranged to align with the outer wall of the body above said band to permit said passage being molded as part of a core forming the rear side.

ABRAHAM ABRAMSON.
